UNITED STATES PATENT OFFICE

103,757

DESIGN FOR A CAKE KNIFE

Gilbert E. White, Milwaukee, Wis.

Application April 17, 1936, Serial No. 62,175

Term of patent 7 years

To all whom it may concern:

Be it known that I, Gilbert E. White, a citizen of the United States, residing at Milwaukee, in the county of Milwaukee and State of Wisconsin, have invented a new, original, and ornamental Design for Cake Knives, of which the following is a specification, reference being had to the accompanying drawing, forming part thereof.

The figure is a view in perspective of a cake knife, showing my new design. The dominant feature of the design resides in the blade portion of the knife.

I claim:

The ornamental design for a cake knife, as shown and described.

GILBERT E. WHITE.
